THREAD ADVANCING REEL

Richard W. Stanley, Drexel Hill, Pa., and Carl A. Castellan, Wilmington, Del., assignors to American Viscose Corporation, Wilmington, Del., a corporation of Delaware

Application September 24, 1946, Serial No. 698,918

6 Claims. (Cl. 28—71.7)

1

This invention relates to thread-advancing reels which may be used for the production of a yarn store which is continuously advanced axially of the periphery of the reel, during which time it may be subjected to fluid treatment in the manner and for the purposes conventional in the art. The main object of the present invention is to provide an improved reel of as simple construction as possible. This is for the purpose of rendering reels of the type disclosed more economical and hence more commercially practicable when it is desired to employ a reel of short axis of cantilever form, such as may be adapted to replace a godet and associated wrap-displacing guide. Other objects and advantages of the invention will be apparent from the drawing and description thereof hereinafter.

In the drawing, which is illustrative of the invention,

Figure 1 is a transverse cross-section of a preferred embodiment of the reel,

Figure 2 is a section on line II—II of Figure 1, and

Figure 3 is a detail looking from line III—III of Figure 1.

As shown, the reel is mounted for rotation about a fixed shaft 2 and comprises two sets of thread-carrying bars 3 and 4 respectively.

The set of bars 3 may be in the form of a cylindrical cage with the bars 3 extending laterally from the ring 5 which may be formed integrally with the bars or secured thereto. The outer peripheral surfaces of the bars 3 lie substantially in a cylindrical surface concentric with the axis of shaft 2. The cage is secured to a web or plate 8 by means of cap screws 9. The hub 10 is secured to the driving spindle 11 by means of a nut 12. A bushing 13 is provided between the spindle 11 and the fixed shaft 2 and is so constructed that the bars 3 are concentric with and rotate about the axis of shaft 2.

The bars 4 are secured to supporting elements 14 which extend downwardly therefrom and are held against bearing elements 15 and 16 which are spaced axially from each other and are carried upon a central sleeve or bushing 17 fixedly secured to the shaft 2 such as by means of nut 18 and/or key 1. The bearing surfaces of the central sleeve 17 which carry the bearing members 15 and 16 have a common center which is eccentric with respect to the axis of shaft 2. Bearing element 15 is rotatable about the sleeve 17 but element 16 is a cam fixed thereto by a key or wedge 6. The bearing member 15 may be provided with an arcuate groove comprising a plurality of seats

2

18 for receiving the complementarily formed convex portion 14a of the supporting elements 14. The cam 16 may have a peripheral groove having an arcuate contour as shown.

5 An annular plate 20 is secured to sleeve 17 by screws 20a has a plurality of radially extending axially projecting lugs 21. The radial portions of the supporting elements 14 work slidably within the guideways formed between adjacent lugs 21. 10 thereby limiting angular movement of the bars 4 relative to the bearings 15 and 16. Garter springs 22 and 23 hold the base of the supporting elements 14 in contact with the bearing members 15 and 16 respectively.

15 A plurality of bosses 24 extending inwardly of the plate 8 carry the ring 25 supporting a plurality of pins 26 which project into apertures 27 (see Figure 3) in the plate 20. The apertures 27 are elongated radially sufficiently to allow for 20 the relative eccentricity of the pins 26 to the plate 20 during rotation thereof.

25 A flexible seal 28, such as rubber, synthetic rubber, or the like, is secured to the ring 5 by means of cap screws 9 and to the bars 4 which have bosses 29 adapted to protrude through suitable openings in the seal 28. As shown in the drawing, the seal has a radially inwardly extending portion terminating in the generally central reinforcing ring or bead 28a. This cup-shaped 30 seal 28 overlaps and thereby co-operates with a fixed sealing ring 28b secured between two nuts 30 and 31 on the shaft 2.

35 There may be carried on the outer end of shaft 2, as between nuts 32 and 33, a flange 34 carrying a doffing ring 35, the inner end of which extends inwardly of the outer ends of the bars 3 and the outer end is provided with an outwardly turned flange 36. Optionally, the ends of bars 3 may be provided with protuberances 37 to prevent any 40 turns of thread from depositing upon the doffing ring 35 unaided by the operator. Such protuberances may be omitted if it is desired to have the thread turns forced off the bars by pushing action of bars 4.

45 The actuating surface of the cam 16 may have a dwell portion extending for about 90° to 270° from the base of the drop, and such dwell may advantageously be concentric with the axis of the bearing surfaces on sleeve 17, the rise occurring 50 in the remainder of the cycle. As shown, the dwell extends about 130° and is concentric with the axis of the bearing surfaces on sleeve 17; the rise occurs in the remainder of the cycle, that is, about 230°, leaving a negligible arc for 55 the drop. As viewed in Figure 2 with the eccen-

tric axis vertically below the concentric of shaft 2, the drop in the cam may occur at any position in the upper left quadrant, but preferably between that shown and that vertically above shaft 2. The cam rise may start at any position after the eccentric bars 4 first take the thread from the concentric bars 3 but before the concentric bars can take back the thread, that is, roughly in the lower two quadrants of Figure 2, preferably within in the lower right quadrant.

In operation, spindle 11 is driven, thereby driving the concentric cage of bars 3. The rotation of the concentric cage is transmitted to the eccentrically mounted bars by means of pins 26 engaging slots 27 in the plate 28 and by virtue of the guiding lugs 21 carried by the plate 28 which prevent lagging of the bars 4. During rotation, bars 4 alternately protrude and recede from the general periphery of the concentric cage of bars 3 and during such protrusion each bar 4 is rocked generally about an axis at the center of curvature of the curved foot portion 14a by virtue of the action of cam 16. Since the rocking action lifts each turn of the thread helix carried on the reel by means of the eccentric bars 4 through an arc such that the thread-carrying surfaces of the eccentric bars can recede into the surface defined by the concentric bars 3 without transferring the thread turns back thereto, it will be noted that, because of the eccentric bearing 14a for the supporting elements 14 of the eccentric bars 4, during the return arc of the bars 4 occurring at the drop in the cam, the concentric bars 3 receive the thread turns before the arc is completed, thereby causing advance of the turns axially toward the outer end of the reel.

Although a cantilever form of reel is shown, that is, one which is supported at one end only, the reel construction is adaptable also to reels supported at both ends and capable of supporting a great number of windings spaced longitudinally of the bars thereof. As appears from the drawing and description thereof, the reel is of simple and inexpensive construction and therefore most advantageously adaptable for use when a small number of turns are to be handled thereby.

It is to be understood that changes and variations may be made without departing from the spirit and scope of the invention as defined in the appended claims.

We claim:

1. A thread-advancing reel comprising a set of spaced bars rotatable about an axis, a second set of spaced bars interdigitating with the bars of the first set, means for supporting the second set of bars rotatably on an axis of rotation eccentric to that of the first set, each of the bars of the second set being mounted on the supporting means pivotally on a single axis transverse of the axis of rotation of the second set of bars, a fixed cam comprising an actuating surface having a gradual rise through an arc greater than 90° followed by a drop through an arc of less than 90° and then followed by a dwell between the drop and the rise, said cam being spaced axially of the reel from the plane of the pivotal axes of the bars of the second set, and means for rotating the bars whereby the bars of the second set are rocked about their pivotal axes by said fixed cam.

2. A thread-advancing reel comprising a set of spaced bars rotatable about an axis, a second set of spaced bars interdigitating with the bars of the first set, means for supporting the second set of bars rotatably on an axis of rotation eccentric to that of the first set, each of the bars of the

second set being mounted on the supporting means pivotally on a single axis transverse of the axis of rotation of the second set of bars, said supporting means comprising a fixed cam comprising an actuating surface having a gradual rise through an arc greater than 90° followed by a drop through an arc of less than 90° and then followed by a dwell between the drop and the rise, said cam being spaced axially of the reel from the plane of the pivotal axes of the bars of the second set, and means for rotating the bars whereby the bars of the second set are rocked about their pivotal axes by said fixed cam.

3. A thread-advancing reel comprising a set of spaced, longitudinally extending bars rotatable about an axis, a second set of spaced longitudinally extending bars interdigitating with the bars of the first set, means for supporting the second set of bars rotatably on an axis of rotation eccentric to that of the first set, said second set of bars being mounted on the supporting means pivotally on axes transverse of the axis of rotation thereof, a fixed cam comprising an actuating surface having a gradual rise through an arc greater than 90° followed by a drop through an arc of less than 90° and then followed by a dwell between the drop and the rise, said cam being spaced axially of the reel away from the pivotal axes of the second set of bars, and the second set of bars being arranged to bear against the fixed cam.

4. A thread-advancing reel comprising a set of spaced bars rotatable about an axis; a second set of spaced bars interdigitating with the bars of the first set; means for supporting the second set of bars rotatably on an axis of rotation displaced from that of the first set comprising two axially spaced bearing members, one of the members being rotatable upon said displaced axis, the other being a fixed cam comprising an actuating surface having a gradual rise through an arc of greater than 90° followed by a drop through an arc of less than 90° and then followed by a dwell between the drop and the rise supporting elements for the bars of the second set resting against both bearing members and slidably relative thereto, guide means slidably engaged by the supporting elements for limiting the angular movement of the second set of bars relative to the bearing members; and means for rotating the bars whereby such rotation rocks the bars of the second set with respect to their supporting means to effect alternate protrusion and recession thereof with respect to the bars of the first set and to thereby advance windings of thread carried on the reel axially thereof.

5. A thread-advancing reel comprising a set of spaced bars rotatable about an axis; a second set of spaced bars interdigitating with the bars of the first set, a fixed shaft, a spindle rotatable on the shaft for driving the bars of the first set about its axis; a sleeve fixed to the shaft and having spaced bearing surfaces having a common axis of revolution eccentric to that of the shaft, two axially spaced bearing members carried on the surfaces, one of said members being rotatable upon the sleeve, the other being a cam fixed thereto comprising an actuating surface having a gradual rise through an arc of greater than 90° followed by a drop through an arc of less than 90° and then followed by a dwell between the drop and the rise, supporting elements for the bars of the second set, and means for holding the supporting elements in engagement with the bearing members.

6. A thread-advancing reel comprising a set of

spaced bars rotatable about an axis; a second set of spaced bars interdigitating with the bars of the first set, a fixed shaft, a spindle rotatable on the shaft for driving the bars of the first set about its axis; a sleeve fixed to the shaft and having spaced bearing surfaces having a common axis of revolution eccentric to that of the shaft, two axially spaced bearing members carried on the surfaces, one of said members being rotatable upon the sleeve, the other being a cam fixed thereto comprising an actuating surface having a gradual rise through an arc of greater than 90° followed by drop through an arc of less than 90° and then followed by a dwell between the drop and the rise, supporting elements for the bars of the second set, spring means for holding the supporting elements in slidably engagement with the bearing members, guide members rotatable with

one of said bearing members having radial guide-ways slidably engaged by the supporting ele-ments for limiting the angular movement of the second set of bars relative to the bearing mem bers.
